DESIGN FOR A NEWEL POST FOR BOWLING BALL RACKS OR THE LIKE

Andrew L. Henkel and Burke M. Ewing, Chicago,
Ill., assignors to The Brunswick-Balke-Col-
lender Company, Chicago, Ill., a corporation of
Delaware

Application April 10, 1940, Serial No. 91,580

Term of patent 14 years

To all whom it may concern:

Be it known that we, Andrew L. Henkel and Burke M. Ewing, both citizens of the United States and both residing in the city of Chicago, in the county of Cook, State of Illinois, have jointly invented a new, original, and ornamental Design for a Newel Post for Bowling Ball Racks or the Like, of which the following is a specification, reference being had to the accompanying drawing, forming a part thereof.

Figure 1 is a side elevational view of a newel post for bowling ball racks or the like, showing our new design;

Figure 2 is a front elevational view thereof;

Figure 3 is a top plan view thereof.

We claim:

The ornamental design for a newel post for bowling ball racks or the like, as shown.

ANDREW L. HENKEL.
BURKE M. EWING.
